DESIGN FOR A DRINKING FOUNTAIN OR
SIMILAR ARTICLE

Robert H. Tull, Springfield, Mass., assignor to
Westinghouse Electric Corporation, a corpora-
tion of Pennsylvania

Application November 30, 1946, Serial No. 135,194

Term of patent 14 years

(Cl. D67—4)

To all whom it may concern:

Be it known that I, Robert H. Tull, a citizen of the United States, residing at Springfield, in the county of Hampden and State of Massachusetts, have invented a new, original, and ornamental Design for a Drinking Fountain or Similar Article, of which the following is a specification, reference being had to the accompanying drawing, forming a part thereof.

Fig. 1 is a front elevation of the drinking fountain or similar article, showing my design;

Fig. 2 is a side elevation;

Fig. 3 is an enlarged fragmentary plan view, showing the upper front edge; and

Fig. 4 is an enlarged sectional view of the front wall of the drinking fountain taken as indicated at line IV—IV of Fig. 1.

The characteristic features of the design re-side in the portions shown in full lines in the drawing.

I claim:

The ornamental design for a drinking fountain or similar article, substantially as shown and described.

ROBERT H. TULL.
